UNITED STATES PATENT OFFICE

161,415

BROOCH OR SIMILAR ARTICLE

Marcel Boucher, Eltingeville, N. Y.

Application July 21, 1950, Serial No. 11,299

Term of patent 3½ years

(Cl. D45—19)

To all whom it may concern:

Be it known that I, Marcel Boucher, a citizen of the United States, residing at Eltingeville, in the county of Richmond and State of New York, have invented a new, original, and ornamental Design for a Brooch or Similar Article, of which the following is a specification, reference being had to the accompanying drawing forming part thereof.

In said drawing:

Fig. 1 is a front view of a brooch or similar article.

Fig. 2 is a side view of the same.

Fig. 3 is a top view of said brooch.

I claim:

The ornamental design for a brooch or similar article, as shown.

MARCEL BOUCHER.
